(57) **CLAIM**

The ornamental design for a combined lid and handle for a can, as shown and described.

DESCRIPTION

FIG. 1 is a perspective view of the top, front and one side of a combined lid and handle for a can showing my new design;

FIG. 2 is a front elevation view thereof;

FIG. 3 is a rear elevation view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a perspective view similar to FIG. 1 with the pivotal lid pivoted to an open position;

FIG. 9 is a perspective view of a second embodiment of the combined lid and handle for a can, the sole difference residing in the top surface aperture and in the hinge; and, FIG. 10 is a perspective view similar to FIG. 9, with the slide in an open position.

The broken line showing of a can is for illustrative purposes only and forms no part of the claimed design.
